UNITED STATES PATENT OFFICE.

EMERY PRIME AUGER, OF CORINTH, MISSISSIPPI, ASSIGNOR OF ONE-HALF TO JOSEPH D. OZIER, OF CORINTH, MISSISSIPPI.

CONCRETE-BLOCK MACHINE.

No. 914,367.

Specification of Letters Patent.

Patented March 2, 1909.

Application filed September 5, 1908. Serial No. 451,820.

To all whom it may concern:

Be it known that I, EMERY PRIME AUGER, a citizen of the United States, and a resident of Corinth, in the county of Alcorn and State of Mississippi, have made certain new and useful Improvements in Concrete-Block Machines, of which the following is a specification.

My invention is an improved machine for making blocks of concrete for use in buildings of various kinds, employing concrete material, and it consists in the combinations, constructions and arrangements hereinafter described and claimed.

An object of my invention is to provide a device in which the block may be molded and then by the use of a cam lever, the sides of the mold can be loosened and let down vertically, leaving the molded block upon the base or table from which it can be readily removed.

A further object of my invention is to provide means by which the sides of the mold may be moved simultaneously, so that there will be no danger of binding the latter against the table.

A further object of my invention is to provide a device in which the depth of the mold can be quickly and accurately changed to suit the various requirements so as to produce blocks of varying thicknesses.

My invention is illustrated in the accompanying drawings, in which—

Figure 1 is a perspective view showing the device in position to receive the concrete filling. Fig. 2 is a plan view of an end portion of the device showing the mold in its locked position. Fig. 3 is a similar view showing the mold in its unlocked position. Fig. 4 is a side view of the device in its lower position, and Fig. 5 is a transverse sectional view at right angles to Fig. 4.

Referring now to the drawings, a rectangular base is provided consisting of the end members 1 and the side members 2. Extending upwardly at the four corners of the frame are the uprights 3. Parallel with the side members 2 are the braces 4. The latter are secured to the corner members 3 and project beyond said members at one end of the frame to form a support for the bearing-board 5. A similar bearing-board 6 is supported by the opposite ends of the strips 4 as is clearly shown in Figs. 1 and 4. A transverse brace 7 is located centrally of the ma-

chine and is carried by the side members 4. The frame thus far described constitutes the base of a table, which is provided with a top 8 and has downwardly extending side and end pieces 9 and 10, respectively, which serve as guides for the sides of the mold as will be hereinafter explained.

The mold itself consists of a rectangular box-like structure having the side pieces 11 and the end pieces 12. Both the side pieces 11 and the end pieces are provided with outwardly projecting shelf portions 13 and 14, respectively, protected by the upwardly extending rims 15 and 16.

The side portions of the mold are movable 70 relatively to the end portions of the same, so that they may be adjusted to and from the latter. The means by which this is accomplished is clearly shown in Figs. 2 and 3. It consists in the provision of the rods 17 and 18 75 secured to the sides 11 at 19, and having curved ends pivotally secured at 20 and 21 respectively, to a clamping lever 22. Fig. 2 shows the sides in their locked position. In this position the lever 22 is thrown over toward the left, thereby bringing the pivotal connections 20 and 21 of the rods 18 and 17 in line, thereby drawing the ends against the sides and locking the latter. In Fig. 3 the lever is shown pulled outwardly, thereby 85 pushing the rods 17 and 18 outwardly and forcing the sides 11 away from the ends.

The means for lowering and raising the mold frame consists of a series of actuating levers. Referring now particularly to Fig. 1, 90 it will be seen that on the bearing pieces 5 and 6 are journaled the two bent levers 23 and 24 respectively, the journals for the latter consisting of strips of metal fastened to the bearing-boards and bent around to provide a suitable bearing for the rods. The levers 23 and 24 are bent at a right angle at 25 and the shorter arms of the levers are bent laterally to pass through the bearings at each end of the bearing supports 5 and 6 and on the other side of the machine are bent at right angles again to form arms similar to the short arms. The bent portions are attached to swinging links 26 by means of a pivot 27'. The links 26 are pivotally attached to one of the side 100 members 11 in the same manner as the links 27 are attached to the side members 11 on the opposite side.

The links 27 are pivotally attached to the levers 23 and 24 at 28 and 29, respectively. 110

a cross bar 30 extends between the two levers 23 and 24 and is pivotally secured thereto so that both levers may have simultaneous movements. The upper ends of the levers 23 and 24 are bent to form handles 31.

In order to provide a support for the movable sides of the mold in their shifted positions, I have arranged the rods 32 and 33 on either side of the frame. These rods are in reality made of one piece and constitute the upright arms of a U-shaped rod, whose connecting member 34 is journaled on the side of the base members 2, as clearly shown in Figs. 1 and 5. Upon the rods 32, 33 are arranged the clamping lugs 35. These lugs are movable relatively of the rods and may be secured in any position by means of the set screws 36. The rods 32 and 33 may be shifted toward and from the frame to bring the stops 35 into line with the movable mold so that the latter can rest upon the stops. In order to shift the rods I have provided the treadle 37, which is pivoted at 38 in a slot in the longitudinal member 4. The opposite end of the treadle lever is connected by a link 39 to a pair of pivoted arms 40 and 41 at their pivotal connection. The arms 40 and 41 are secured to the rods 34 on either side of the machine. On depressing the treadle 37, the arms 40 and 41 are swung upwardly by the link 39, thereby shifting the uprights 32 and 33, together with their stops 35, out of the way of the movable mold, thereby permitting it to be lowered into the position shown in Fig. 5. On the release of the treadle 37 the arms 41 and 40 are put under spring tension by means of the spring 42, which is secured to the cross brace 7. It will be seen therefore that when the mold is again lifted, the upper stops 35 will at once spring underneath the mold and support it.

Having thus described the various parts of the device, the operation will be easily understood. In practice the device is raised by means of the levers 23 and 24 in the position shown in Fig. 1. In this figure dividing pieces 43 are shown in position for molding window sills. With the molds in position, the charge of wet concrete is put in and packed down in the customary manner, the clamping lever 22 being turned so as to bring the sides and ends closely together. After the material in the molds has been subjected to sufficient pressure, the clamps 22 are drawn outwardly into the position shown in Fig. 3, thereby loosening the sides of the mold and permitting it to be easily lowered into the position shown in Fig. 4. This is accomplished by means of the levers 23 and 24. The handles 31 are grasped and they are swung from right to left. An inspection of the drawings will show that the movement of the handles in this direction will cause the mold to descend, the links 26 and 27 on either

side of the mold moving uniformly downward and allowing the mold to descend without tilting. In order to permit the descent of the mold the treadle 37 is pressed in the manner already described, thereby throwing the upper stops 35 out of engagement with the mold and allowing it to assume the position shown in Fig. 5. As the mold descends, the concrete blocks, together with the dividing members 43, are left in position upon the top of the table, the latter of course forming the bottom of the mold. From thence the blocks can be easily transported to the place in which they are to be set to thoroughly harden.

Obviously other forms of mold than that shown herein could be used with my improved concrete block machine.

The main object of my invention, as has been stated before, is to provide a machine in which the sides of the mold may be drawn downwardly away from the molded material leaving the latter in a perfectly molded condition and free from the outside mold upon the table.

I claim—

1. In a concrete block machine, a mold provided with a stationary bottom and sides and ends relatively movable thereto, levers for moving said sides and ends, links for maintaining the movement of all parts in parallelism, stops for retaining the movable parts in one position, and a treadle for withdrawing said stops and permitting the downward movement of the sides and ends past the bottom.

2. In a concrete machine, a rectangular mold provided with a stationary bottom, sides and ends relatively movable thereto, means for clamping said sides and ends together, means for expanding the sides, a pair of pivoted levers provided with laterally extending handles, links pivoted to said levers and to the lower ends of the side members, pivoted rods provided with upper and lower stop members arranged to engage the side at the four corners thereof, and a treadle for withdrawing said stops simultaneously and for permitting the downward movement of the sides and ends when said levers are operated.

3. In a concrete block machine, a rectangular mold provided with a stationary bottom, sides and ends relatively movable thereto, said sides and ends being provided with stepped joints, means for locking the sides to the ends at said joints, means for unlocking and for separating the sides from the ends and means for lowering the sides and ends past the stationary bottom.

4. In a concrete block machine, a rectangular mold provided with a stationary bottom, separable sides and ends, each provided with a flanged shelf, means for locking the sides to the ends and for unlocking and separating

the same, spring-actuated upright rods provided with stops at each corner of the mold arranged to support the sides and ends in their upper position, a treadle for rocking said rods to permit the downward movement of the sides and ends, and a system of pivoted levers for moving the sides and ends down- wardly past the stationary bottom and for maintaining the moving parts in parallelism.

EMERY PRIME AUGER.
